UNITED STATES PATENT OFFICE

HANS LEEMANN AND WALTER WEHRLI, OF BASEL, SWITZERLAND, ASSIGNORS TO THE FIRM "CHEMICAL WORKS FORMERLY SANDOZ", OF BASEL, SWITZERLAND

MANUFACTURE OF SULPHUR DYESTUFFS

No Drawing. Application filed June 26, 1930, Serial No. 464,118, and in Great Britain July 6, 1929.

The present invention relates to the manufacture of brownish-red, red, reddish-violet and violet sulphurized dyestuffs by heating hydroxylated azines and their derivatives 5 with alkali polysulphides.

It is already known that from various azines, for instance from hydroxylated azines and their derivatives, safranines and their derivatives, iso-rosindulines etc. sulphurized, 10 violet-brown to red-brown dyestuffs can be obtained. It is also known that the color shades and the fastness properties of these dyestuffs are improved when the so-called melting process is carried out in presence of 15 certain metals or metal salts, such as copper, nickel, cobalt, or their salts and compounds.

We have now made the surprising observation that far better results are obtained if, instead of the metals or compounds above referred to as having already been used as addition to the meltings, molybdenum or molybdenum compounds are employed. This was not to be foreseen, because until now molybdenum or molybdenum compounds never 20 have been used in the manufacture of sulphurized dyestuffs.

The new dyestuffs produced in the above described manner, that is when the melting process takes place in the presence of molybdenum or molybdenum compounds give 25 much clearer and redder dyes when dyeing in a sodium sulphide bath in comparison with the known sulphurized dyestuffs obtained by melting the same azines with the addition of one of the metals above referred 30 to or their salts. For example amino-hydroxytolazine which, when melted in presence of copper or copper salts, yields red-brown sulphurized dyestuffs, when however being melted in presence of molybdenum or 35 molybdenum compounds, yields bluish dark red dyestuffs. The action of molybdenum in this case is really surprising and the possibility of producing from the same primary 40 material remarkably redder dyestuffs is of great practical value and constitutes a real progress. A further advantage of the dye- 45 stuffs produced with the new dyestuffs is their valuable property of being fast or stable in 50 storing.

Various molybdenum compounds can be employed, for example, molybdic acid, alkali-metal or ammonium molybdates, phosphomolybdic acid and so on, but the invention is not limited to the compounds mentioned. 55

In the new process, we may employ as azines those azines which, when melted in the already known manner, in presence or not of a metallic compound, give from reddish-brown, reddish, bordeaux-red, reddish-violet to violet sulphurized dyestuffs. Especially good results are obtained with hydroxylated azines and their alkyl-, aryl-, halogen- and like derivatives, or their carboxylic or sulphonic acids. 60 65

The conditions of the melting process (temperature, time, proportion of alkali polysulphide, quantity of the molybdenum compounds) may be modified within wide limits. The process can further be carried out in 70 presence of the usual fusing or dissolving agents, as glycerine or alcohol, or under pressure.

The invention is illustrated by the following examples, the parts being by weight: 75

Example 1

86 parts of amino-hydroxyphenazine

80

are dissolved in 80 parts of water and 171 85 parts of a 30% solution of caustic soda and allowed to run into a hot solution of sodium polysulphide prepared from 173 parts of sulphur, 325 parts of crystallized sodium sulphide and 325 parts of water. Thereupon, 90 28 parts of molybdic acid are added and the water is partially evaporated, until the boiling point has reached 110° C. Then the melt is heated for 30-32 hours under a reflux condenser until the dyestuff has the desired 95 shade. The raw product can be used directly or the dyestuff can be isolated as usual. It dyes cotton fibres from a sodium sulphide bath clear bluish Bordeaux-red shades of 100 good fastness.

Example 2

58 parts of amino-hydroxytolazine

are dissolved in 60 parts of water and 38 parts of a 30% solution of caustic soda and 10 allowed to run into a hot solution of sodium polysulphide prepared by dissolving 180 parts of sulphur in 282 parts of sodium sulphide (60%) and 500 parts of water. After 15 addition of 23 parts of ammonium molybdate, dissolved in 60 parts of water, the water is partially evaporated, until the boiling point has reached 120° C. Then the melt is heated for 16-20 hours under reflux until the dyestuff has the desired shade. The product dyes 20 cotton fibre from a sodium sulphide bath dark red shades.

Example 3

If in the Example 2 instead of 23 parts of ammonium molybdate 24 parts of phosphomolybdic acid are employed, the same dyestuff is obtained.

Example 4

30 If in the Example 2 instead of 58 parts of amino-hydroxytolazine the same quantity of the azine of the formula:

prepared by treating the azine

under pressure in an aqueous solution, is employed, a quite similar dyestuff is obtained.

Example 5

45 If in the Example 2 instead of 58 parts of amino-hydroxytolazine the same quantity of amino-hydroxytolazine carboxylic acid

is employed, almost the same dyestuff is obtained.

Example 6

If in the Example 2 instead of amino-hydroxytolazine the corresponding quantity of dichloroamino-hydroxytolazine of the formula:

is employed, a quite similar dyestuff is obtained.

Example 7

If in the Example 2 the amino-hydroxytolazine is replaced by the same quantity of 70 ethosafarinone

a dyestuff results, which dyes the cotton fibre from a sodium sulphide bath clear bluish-red shades.

80 What we claim is:

1. A process for the production of sulphur dyestuffs, which comprises heating such hydroxylated azines that beside the azine ring do not contain other heterocyclic rings, with sodium hydroxide and sulphur in presence of substances containing molybdenum.

85 2. A process for the production of sulphur dyestuffs, which comprises heating amino derivatives of such hydroxylated azines, that beside the azine ring do not contain other heterocyclic rings, with sodium hydroxide and sulphur in presence of substances containing molybdenum.

90 3. A process for the production of sulphur dyestuffs, which comprises heating amino-hydroxyphenazine with sodium hydroxide and sulphur in presence of substances containing molybdenum.

95 4. A process for the production of sulphur dyestuffs, which comprises heating amino-hydroxyphenazine with a sodium polysulphide in presence of molybdc acid.

100 5. The sulphur dyestuffs deriving from hydroxylated azines which beside the azine ring do not contain other heterocyclic rings, and containing molybdenum, said dyestuffs being in dry state generally dark powders, soluble in concentrated sulphuric acid with a blue-violet to red violet coloration and which dye cellulose fibres from a sodium sulphide bath brownish-red, red, reddish-violet to violet shades.

110 6. The sulphur dyestuff, containing molybdenum, obtained from amino-hydroxyphenazine with sodium polysulphide in presence of molybdc acid, and which is a violet-brown powder, soluble in concentrated sulphuric acid with a blue-violet color and dyes cellulose fibres from a sodium sulphide bath red-brown shades.

In witness whereof we have hereunto signed our names this 17th day of June, 1930.

HANS LEEMANN.

WALTER WEHRLI.
